UNITED STATES PATENT OFFICE.

HERMAN J. H. HUBER, OF SCHENECTADY, NEW YORK, ASSIGNOR TO GENERAL ELECTRIC COMPANY, A CORPORATION OF NEW YORK.

ELECTRIC SWITCHING APPARATUS.

Application filed October 8, 1921. Serial No. 506,235.

To all whom it may concern:

Be it known that I, HERMAN J. H. HUBER, a citizen of the United States, residing at Schenectady, in the county of Schenectady, 5 State of New York, have invented certain new and useful Improvements in Electric Switching Apparatus, of which the following is a specification.

My invention relates to armature resetting mechanisms for electromagnets and more particularly to improvements in armature resetting mechanisms for electroresponsive devices arranged to control the operation of electric switches in response to abnormal 10 conditions. An object of my invention is to provide an improved means for moving the armature of an electromagnet to a position where the armature may be held by the electromagnet upon energization thereof to a 15 predetermined amount and to provide improved resetting means which in the resetting movement releases the armature of the electromagnet when the armature has reached a position in which it may be held 20 by the electromagnet whereby the armature is free to move to unattracted position whenever the energization of the electromagnet falls to a predetermined amount.

Another object of my invention is to provide in a combination comprising a switch and electroresponsive means for controlling the operation of the switch, an improved means adapted to be operated after the switch has been opened due to an abnormal 30 circuit condition, to reset the electroresponsive device in switch controlling position during the closing movement of the switch. A further object of my invention is to provide a resetting means which has a positive 35 action that can not interfere with the switch controlling movements of the electroresponsive device and which is simple in construction and readily applicable to the switch structure.

40 My invention will be better understood from the following description taken in connection with the accompanying two sheets of drawings, and its scope will be pointed out in the appended claims.

45 Figure 1 is a part elevation of an electric switch in the closed position controlled by an electroresponsive device embodying my invention; Fig. 2 shows in perspective the resetting lever of the embodiment of my invention shown in Fig. 1; Fig. 3 is a perspec-

tive of the embodiment of my invention shown in Fig. 1 showing the electroresponsive device after the switch has been opened; and Fig. 4 is an elevation similar to Fig. 1 with the parts in one of the positions they 60 occupy during the switch closing movement.

Figs. 1 and 4 show an embodiment of my invention in an electroresponsive device 1 which may be of an undervoltage type having a hinged armature 2 arranged to mechanically trip an electric switch 3 shown for illustration as a switch of the type having contacts separable in oil or like fluid. The switch 3 is supported by a bracket 4 secured to a frame 5 and is shown as having an operating mechanism arranged to be actuated for closing the switch 3 by the plunger of a solenoid mounted in a casing 6 which is supported by a bracket 7 secured to the frame 5. The switch operating mechanism comprises an operating shaft 8 journaled in the bracket 7 and an operating lever 9 pivoted on a pin 10 in the bracket 7. One arm 11 of the operating lever 9 is connected to a contact operating lever 12 through a link 13 and an underset toggle comprising links 14 and 15, the toggle link 15 and the lever 12 being pivotally mounted on the bracket 4. Rigidly secured to the operating shaft 8 is a crank comprising two arms 17 and 18 or 85 if desired these arms may be separate members each rigidly secured to the operating shaft 8. Pivotally connected to the arm 17 and forming therewith a toggle, underset when the switch is closed, is a link 19 which 90 is pivotally connected to the operating lever 9 by a pin 20. An overset toggle comprising links 21 and 22 pivotally connected to the arm 18 and the bracket 7 respectively and to each other by a pin 23 serves to hold the 95 switch operating mechanism in switch closed position. A stop or pin 24 on the free end of the link 21, abutting the link 22 holds the toggle 21-22 in its overset or thrust transmitting position. Obviously, with this arrangement and with the parts in the switch closed position as shown in Fig. 1 the collapsing of the toggle 21-22 will cause the toggle 17-19 to collapse thus allowing the operating lever 9 to turn counterclockwise on 100 the pin 10 thereby collapsing toggle 14-15, turning contact operating lever 12 clockwise and opening the switch 3. To close the switch 3, the operating lever 9 is turned clockwise. Obviously this may be done by 105

110

turning the operating shaft 8 counterclockwise but with the arrangement shown the operating lever 9 is adapted to be actuated directly by the plunger of a solenoid mounted 5 in the casing 6. The solenoid, when energized, raises the plunger with considerable force, the plunger pushing against a roller journaled in the lower side of the operating lever 9 intermediate the ends 10 and 20 and there- 10 by turning the lever 9 clockwise or in the direction to close the switch 3.

The means I have shown for tripping the toggle 21-22 comprises an electroresponsive device 1 of the undervoltage type having an 15 electromagnetic structure 25 mounted on a bracket 26. In the arrangement shown the bracket 26 is adapted to be secured to the structure of an overload tripping device 27 supported by the bracket 7, a clearance hole 20 28, see Fig. 3, being provided for the plunger of the overload tripping device 27. The electromagnetic structure 25, when energized under a predetermined voltage condition, is adapted to hold the hinged armature 2 in the 25 closed or attracted position shown in Fig. 1. Inasmuch as it is not convenient in combination with other electroresponsive devices or practical especially in large capacity switches which require relatively heavy structural 30 parts to have the armature 2 sufficiently heavy so that in falling it will trip the toggle 21-22 by its own weight, I provide an energy storing means controlled by the movement of the armature 2 for exerting a 35 force of sufficient magnitude on the toggle link 22 to insure a positive collapsing of the toggle 21-22 when the armature 2 moves to its unattracted position. This means comprises a toggle consisting of a link 29 and one 40 arm of a crank 30 pivoted on the armature hinge pin, the other arm of the crank 30 abutting the armature 2 as it approaches the closed or attracted position. Pivots connected to the link 29 is one arm of a crank 31 45 pivoted on a pin 32 in the undervoltage device 1. The other arm of the crank 31 is pivotally connected by a link 33 to a link 34 also pivotally mounted in the electroresponsive device 1. A biasing means or spring 35 ex- 50 tends between the pivotal connection of links 33 and 34 to a pin 36 in the undervoltage device 1. With this arrangement the movement of the armature 2 to the closed or attracted position actuates the crank 30 to 55 move the toggle 29-30 to its overset position and therefore the linkage comprising crank 31 and links 33 and 34 to a position tensioning spring 35. In order to utilize the energy thus stored in the spring 35 for tripping the toggle 21-22, a tripping lever pivoted at an intermediate point 37 thereof on the undervoltage device 1 has one arm 38 provided with a projecting portion 39 ex- 60 tending directly in the path of movement 65 of the pivotal connection of crank 31 and

link 33. The other arm 40 of the tipping lever projects under the toggle link 22. Therefore, when the armature 2 falls in response to a predetermined voltage condition, a tail 2' on the armature 2 strikes the toggle 70 29-30 and the toggle is collapsed thus releasing the energy stored in the spring 35. The members 31, 33 and 34 move downward with a snap action, the pivotal connection between members 31 and 33 delivering a blow 75 of sufficient force on the projection 39 of the arm 38 of the tripping lever to cause the other arm 40 to come up against the toggle link 22 and trip the toggle 21-22 thereby causing the switch 3 to open. 80

Manifestly the toggle 21-22 may be tripped by one or more electroresponsive devices operative in response to different abnormal conditions such as overload, undervoltage, etc. The form of electroresponsive device which I have illustrated is of the hinged armature undervoltage type. Devices of this type do not inherently reset themselves automatically after the circuit controlled by the switch has been opened but 90 must be reset either manually or automatically before the switch can be closed. It is not always convenient or possible to reset the armature of such devices manually, especially in remotely controlled switches and if 95 the armature is manually reset, it may be possible for the operator to hold the switch closed with abnormal conditions prevailing on the circuit controlled by the switch. If the armature is reset automatically in the 100 switch closing movement the switch can readily be arranged to be trip-free-from-the-hand to prevent the operator from holding the switch closed when abnormal conditions prevail. 105

According to my invention, I provide therefore an armature actuating mechanism for automatically resetting the armature 2 of the undervoltage device 1 when the switch operating mechanism is actuated to close the 110 switch 3. The resetting mechanism comprises a resetting member or lever 41 adapted to be rigidly secured to the operating shaft 8 by any suitable means such as a set screw 42. The resetting lever 41 is provided 115 with bearings 43 and 44 in which is mounted a shaft 45 having secured thereto between the bearings 43 and 44, a hub 46 and at one end beyond the bearing 43 a cam 47. The hub 46 is provided with two lugs 48 and 49 120 arranged to engage a stop 50 on the resetting lever 41 such that the hub 46 may have an angular movement of substantially 125 ninety degrees. Secured to the hub 46 substantially perpendicularly thereto is a projecting portion or pin 51 on which is rotatably mounted a roller 52 adapted for rolling contact on the outer face of the armature 2 during the counterclockwise rotation of the resetting lever 41. The hub 46 is ar- 130

ranged to be biased in each of two directions by a spring 53 secured to an extension 54 of the resetting lever 41 and to a post 55 mounted on an extension of the hub 46. In each of these positions, the alignment of the spring supports 54 and 55 is such that the spring 53 is slightly off the axis of rotation of the shaft 45. These two positions will be designated respectively as the clear position, see Figs. 1 and 2, and the resetting position, see Figs. 3 and 4. When the hub 46 is in the clear position the roller shaft 51 is turned to a position such that in the switch opening movement, that is clockwise rotation of the operating shaft 8 and therefore of the resetting lever 41, the roller 52 swings clear of the armature 2 in its open position. When the hub 46 is in the resetting position, the roller shaft 51 is revolved substantially ninety degrees from the clear position so that in the switch closing movement, that is counterclockwise rotation of the operating shaft 8 and therefore of the resetting lever 41, the roller 52 rides over the outer face 15 of the armature 2 turning it toward the closed or attracted position as shown in Fig. 4. In order to turn the hub 46 to these two positions, a stop member 56 secured to the undervoltage device 1 is provided with preferably adjustable stops 57 and 58 which engage the cam 47 on the shaft 45 when the resetting lever approaches its limiting positions of travel and turn the shaft 45 against the bias of the spring 53. The initial 20 pulse given the cam 47 by one or the other of the stops 57 or 58 turns the hub 46 so that the spring 53 is moved across the axis of the shaft 43 and the spring 53 biases the hub 46 around into position, one or the other of the 25 lugs 48 or 49 coming to rest against the stop 50.

Assuming the parts in the switch closed position as shown in Fig. 1, the occurrence of voltage below a predetermined amount on the circuit controlled by the switch 3 will cause the undervoltage device 1 to release the armature 2 which in falling causes the toggle 21-22 to be tripped and thereby allows the switch to open as heretofore described. The opening of the switch causes the operating shaft 8 and the resetting lever 41 secured thereto to turn clockwise. As the resetting lever 41 reaches a position below the plane of the armature 2 which has 30 dropped to its open or unattracted position, the cam 47 strikes the stop 57 turning the hub 46 around so that the spring 53 biases the roller 52 into the resetting position with the lug 48 against the stop 50. It is to be 35 noted that this action takes place after the resetting lever 41 has turned past the armature 2 in its open position and the parts of the undervoltage device 1 are in position as shown in Fig. 3. With the turning of the hub 46 as described, the roller 52 is swung

underneath the armature 2 in a position to engage the armature 2 when the resetting lever 41 is turned counterclockwise. In the switch closing movement, the operating shaft 8 turns counterclockwise and the resetting lever 41, secured thereto and turning in the same direction brings the roller 52 against the outer face of the armature 2. As the resetting lever 41 continues its movement the roller 52 rolls over the armature 2 as shown in Fig. 4, moving the armature toward the attracted position. The resetting lever 41 is so set relatively to the operating shaft 8 that the roller 52 rides off the armature 2 in its attracted position when the switch contacts touch. If the voltage is sufficient to retain the armature 2 in the attracted position the final closing movement of the switch 3 turns the resetting lever until the cam 47 strikes the stop 58 thus turning the hub 46 and the roller 52 into the clear position with the spring 53 holding the lug 49 against the stop 50 as shown in Figs. 1 and 2. If, however, the undervoltage device is not sufficiently energized to hold the armature 2 in its attracted position, the armature will fall immediately the roller 52 rolls off its face, that is when the switch contacts touch. Consequently, the switch 3 may open before the resetting lever 41 has 40 reached a position to cause the hub 46 to be rotated into the clear position. In this case when the arm 41 falls back, the roller 52 still in the resetting position strikes the upper face of the armature 2. This turns the hub 46 into the clear position where the spring 53 holds the lug 49 against the stop 50. As the resetting lever 41 continues its movement to full open position, the cam 47 strikes the stop 57 and the hub 46 is again turned into the resetting position with the roller 52 underneath the armature 2.

What I claim as new and desire to secure by Letters Patent of the United States, is:

1. In an apparatus of the class described wherein a movable armature is arranged to cooperate with an electromagnet and to be held in attracted position by said electromagnet upon a predetermined energization thereof and to move away from said magnet when the energization thereof falls to a predetermined value, the combination with said electromagnet and armature, of means for moving the armature to a position in which it may be held by said electromagnet comprising a resetting member, an armature actuating means pivotally mounted thereon arranged upon movement of said resetting member in one direction to engage and move over said armature to move the same toward attracted position and to release the same when the armature has reached a position in which it may be held by the energization of said electromagnet, and devices at the limits of movement of said re-

setting member for moving said armature actuating means on its pivot so that at the completion of the movement of said resetting member in a direction to move said 5 armature into attracted position, said armature actuating means is moved to a position such that upon movement of said resetting member in the reverse direction said actuating means will move clear of 10 the armature and so that at the completion of movement of said resetting member in said reverse direction said armature actuating means is restored to a position to engage 15 said armature upon subsequent movement in the first direction.

2. In an apparatus of the class described wherein a movable armature is arranged to cooperate with an electromagnet and to be held in attracted position by the electromagnet upon a predetermined energization thereof and to move away from the electromagnet when the energization thereof falls to a predetermined value, the combination with said electromagnet and armature of 20 means for moving the armature to a position in which it may be held by the electromagnet, comprising a resetting member, an armature actuating means pivotally mounted thereon arranged upon movement of said 25 resetting member in one direction to engage and move over said armature to move the same toward attracted position and to release the armature when the same has reached a position in which it may be held 30 by the energization of the electromagnet, devices at the limits of movement of said resetting member for moving said armature actuating means on its pivot so that at the completion of the movement of said 35 resetting member in a direction to move said armature into attracted position said actuating means is moved to a position such that upon movement of said resetting member in the reverse direction said armature actuating means will move clear of the armature and so that at the completion of movement of said 40 resetting member in said reverse direction the armature actuating means is restored to a position to engage said 45 armature upon subsequent movement of the resetting lever in the direction to reset said armature, and resilient means arranged to throw said actuating means in one direction or the other upon movement of the 50 same past an intermediate position.

3. In an apparatus of the class described wherein a movable armature is arranged to cooperate with an electromagnet and to be held in attracted position by the electromagnet upon a predetermined energization thereof and to move away from the electromagnet when the energization thereof falls to a predetermined value, the combination with said electromagnet and armature of means 55 for moving the armature to a position in

which it may be held by the electromagnet comprising a resetting member, a hub pivotally mounted thereon and provided with a projecting portion arranged upon movement of said resetting member in one direction to engage and move over said armature to move the same toward attracted position and to release the armature when the same has reached a position in which it may be held by the energization of the electromagnet, and devices at the limits of movement of said resetting member for moving said hub on its pivot so that at the completion of the movement of said resetting member in a direction to move said armature into attracted position said hub is moved to a position such that upon movement of said resetting member in the reverse direction said projecting portion will move clear of the armature and so that at the completion of movement of said resetting member in said reverse direction said projecting portion is restored to a position to engage said armature upon subsequent movement of the resetting member in the direction to reset said armature.

4. In an apparatus of the class described wherein a movable armature is arranged to cooperate with an electromagnet and to be held in attracted position by the electromagnet upon a predetermined energization thereof and to move away from the electromagnet when the energization thereof falls to a predetermined value, the combination with said electromagnet and armature of 100 means for moving the armature to a position in which it may be held by the electromagnet comprising a resetting member, a hub pivotally mounted thereon and provided with a projecting portion, a rotatable member mounted upon said projecting portion arranged upon movement of said resetting member in one direction to engage and roll over said armature to move the same toward attracted position and to roll off the armature when the same has reached a position in which it may be held by the energization of the electromagnet and devices at the limits of movement of said resetting member for moving said hub on its pivot so that at the completion of the movement of said resetting member in a direction to move said armature into attracted position said hub is moved to a position such that upon movement of said resetting member in the reverse 110 direction said rotatable member will move clear of the armature and so that at the completion of movement of said resetting member in said reverse direction said hub is restored to a position such that said rotatable member will engage said armature upon subsequent movement of the resetting lever in the direction to reset said armature.

5. An electromagnet having a hinged armature, a resetting member arranged to be 115

5 moved in one direction to reset said armature, armature actuating means mounted on said resetting member arranged to be moved into each of two positions, in one of which 10 said actuating means is adapted to engage and reset said armature upon the movement of said resetting member in resetting direction and in the other of which said actuating means moves clear of said resetting member, 15 and means for moving said armature actuating means into the clear position upon the completion of the movement of said resetting member in resetting direction and for moving said armature actuating means into 20 armature resetting position upon completion of the reverse movement of said resetting member.

6. In an apparatus of the class described wherein the contacts of an electric switch 20 are adapted to be controlled by an operating mechanism arranged to be held in the switch closed position and adapted to be released to the switch open position in response to the movement of the armature of an electro- 25 magnet when the energization thereof falls to a predetermined value and wherein the armature of the electromagnet is arranged to be held in attracted position by the electromagnet upon a predetermined energiza- 30 tion thereof, the combination with said electromagnet and armature of means for mov- ing said armature to a position in which it may be held by the electromagnet comprising a resetting member, means pivotally mounted on said resetting member arranged 35 upon movement of the resetting member in one direction to engage and move over said armature to move the same toward attracted position and to release the armature in a position where it may be held by the electromagnet substantially at the instant the switch contacts touch, and devices at the limits of movement of said resetting member for moving said pivotally mounted means on its pivot so that at the completion 40 of movement of said resetting member in a direction to reset said armature said pivotally mounted means is moved to a position such that upon movement of said resetting member in the reverse direction said pivotally mounted means will move clear of the armature and so that at the completion of movement of said resetting member in said reverse direction said pivotally mounted means is restored to a position to engage 45 said armature upon subsequent movement of the resetting member in the direction to reset the armature.

In witness whereof I have hereunto set my hand this 7th day of October, 1921.

HERMAN J. H. HUBER.
